UNITED STATES PATENT OFFICE.

GEORGE R. FARRELL, OF LEOMINSTER, MASSACHUSETTS, ASSIGNOR, BY MESNE ASSIGNMENTS, TO STANDARD PYROXOLOID CORPORATION, OF LEOMINSTER, MASSACHUSETTS, A CORPORATION OF MASSACHUSETTS.

TOILET ARTICLE.

Application filed November 15, 1923. Serial No. 675,003.

To all whom it may concern:

Be it known that I, GEORGE R. FARRELL, a citizen of the United States, residing at Leominster, in the county of Worcester and State of Massachusetts, have invented a new and useful Toilet Article, of which the following is a specification.

This invention relates to a toilet article such as a brush, mirror or the like.

The principal objects of the invention are to provide an article of this character formed with a minimum amount of pyroxylin and yet having the appearance of being made of solid pyroxylin and provided with a solid material inside the sheet material of which it is made which will give the necessary solidity and rigidity. This results in the saving of material amounts of pyroxylin and the substitution of a cheaper material inside the article where it cannot be seen.

Reference is to be had to the accompanying drawings, in which—

Fig. 1 is a plan of a hand mirror constructed in accordance with this invention;

Fig. 2 is a sectional view on the line 2—2 of Fig. 1; and

Fig. 3 is a view similar to Fig. 2 showing the application of this invention to a hair brush.

In Figs. 1 and 2, I have shown the invention as comprising a back 10 having a perimeter 11 extending all around it and incurved at its edge. It extends upwardly from the plane back 10 to a slight distance and is provided with a flat top surface 12 extending all around in a plane parallel with the main surface of the back 10. The front 13 of this article is made in the same way and both these parts, instead of being formed as heretofore of a thick piece of pyroxylin, are formed of a thin sheet of pyroxylin preferably not over 40/1000 of an inch in thickness. The edges are made in dies smoothly convex so that they do not have to be trued up or finished. The front instead of having a flat outside surface like the back 10 is provided with a depression 14 for receiving the mirror 15 and a pyroxylin rod 16 for holding it in place.

It will be seen that if the two adjacent surfaces 12 of the front and back which are intended to be of exactly the same shape were abutted together they could be cemented to-

gether and an article of the desired shape 55 made therefrom. But to make a distinctive and attractive article and also to add to its strength and rigidity I place on one of these plane surfaces 12 a flat outline strip 19 of pyroxylin of considerable thickness but only 60 of slight width. It has the outline of the article as shown and projects beyond the edges of the back and front 10 and 13 and also projects within them.

The parts thus far described constitute 65 all the pyroxylin used and if put together in that way would provide a hollow article of very flexible character but I fill the space inside with a plastic material 20 capable of hardening to a condition in which it has 70 a great deal of rigidity. This fills the entire space and gives the article the appearance and strength of one made of solid pyroxylin. It will be understood of course that both the surfaces 12 of the back and 75 front are cemented to opposite sides of the strip 19. This strip is rounded off on its outer surface to give it an attractive appearance. As the convex edges of the front and back lie back a uniform distance from the 80 edge of this strip 19 they do not interfere with the trimming and rounding of the outer edge of the strip 19. This article can be made by the method described in my co-pending Patent No. 1,521,875.

In the form shown in Fig. 3 the invention is illustrated as applied to a hair brush. This is made similar to the mirror but where that has a depression 14 for the glass, this is provided with a series of perforations 90 21 for a number of brush tufts 22. The ends of these tufts stick back into the interior of the article and are surrounded and held by the plastic material 20 which thus co-operate with the tufts to hold them in position. 95 It also surrounds the inwardly projecting edge of the strip 19 to hold that rigidly.

Although I have illustrated and described only two forms of the invention, I am aware of the fact that it can be applied to other 100 articles with variations in form without departing from the scope of the invention as expressed in the claims.

Therefore I do not wish to be limited to the particular article shown but what 105 I do claim is:—

1. As an article of manufacture, a hand mirror having a back of thin sheet pyroxy-

lin inturned at its edge to form a surrounding wall at the edge and having a flat surface at the end of said wall, a front formed in substantially the same way but having a depression for the glass, the two parts being placed together so that their inturned edges register with each other, an outline strip of contrasting pyroxylin inserted between said edges all around the mirror, and plastic material inserted and completely filling the space between the back and front and within the outline strip.

2. An article of manufacture of the class described comprising a back and front of thin sheet pyroxylin, each having a perimeter extending toward the other and of the same size and shape and provided with a plane surface on the edge thereof, and an outline strip of pyroxylin located between the two flat surfaces of said perimeters and projecting beyond them both inwardly and outwardly, and a filling of plastic material inserted therein.

3. An article of manufacture of the class described comprising a back and front of thin sheet pyroxylin, each having its edge extending toward the other and of substantially the same size and shape, an outline strip of pyroxylin of a contrasting appearance located between the two adjacent edges of said front and back and projecting beyond them both inwardly and outwardly and rounded on its outer edge, and a filling of plastic material inserted therein.

4. An article of manufacture of the class described comprising a back and front of thin sheet pyroxylin, of substantially the same size and shape, an outline strip of pyroxylin of a contrasting appearance located between the two adjacent edges of said front and back and projecting beyond them and rounded on its outer edge, and a filling of plastic material inserted therein.

In testimony whereof I have hereunto affixed my signature.

GEORGE R. FARRELL,
